(57) **CLAIM**

The ornamental design for an adjustable reflector socket, as shown and described.

DESCRIPTION

FIG. 1 is a perspective view of an adjustable reflector socket showing the first embodiment of my new design;

FIG. 2 is a front elevational view;

FIG. 3 is a rear elevational view;

FIG. 4 is a left side elevational view;

FIG. 5 is a right side elevational view;

FIG. 6 is a top plan view;

FIG. 7 is a bottom plan view;

FIG. 8 is an exploded perspective view similar to FIG. 1;

FIG. 9 is a vertical sectional view taken along line 9—9 of FIG. 8;

FIG. 10 is a perspective view of an adjustable reflector socket showing the second embodiment of my new design;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is similar to FIG. 9, but having the mounting ring thereof; and,

FIG. 18 is similar to FIG. 2, wherein the adjustable reflector socket is similar to that shown in FIGS. 1-9, but having a modified front end.
